(57) CLAIM

The ornamental design for a front panel for women's pants, as shown.

DESCRIPTION

FIG. 1 is a front and side perspective view of a front panel for women's pants embodying my new design;

FIG. 2 is a front elevational view thereof;

FIG. 3 is a right side elevational view thereof;

FIG. 4 is a left-side elevational view thereof;

FIG. 5 is a rear elevational view thereof;

FIG. 6 is a bottom plan view thereof; and,

FIG. 7 is a top plan view showing internal structure thereof.

The broken lines visible in FIGS. 1-7 are for illustrative purposes to indicate environment only, and form no part of the claimed design.
